Fig. 4

Fig. 3

FIGURE 1 is a top perspective view of a vitamin tablet or similar article embodying my new design;

FIGURE 2 is a plan view thereof, the bottom is a mirror image of the top shown;

FIGURE 3 is an edge view looking up from the bottom of FIGURE 2; and

FIGURE 4 is an edge view taken generally at right angles to one of the edges thereof.

The characterizing feature of my design resides in the specific configuration of the curved recessed surface being congruent with the curved upper surface of the tablet as best illustrated in FIGS. 3 and 4 in the drawing.

I claim:

The ornamental design for a vitamin tablet or similar article, as shown and described.
